DECK HATCH FOR BOATS

Raymond A. Lo Turco, Boca Raton, Fla., assignor to Chris-Craft Corporation, Pompano Beach, Fla., a corporation of Michigan

Filed Sept. 11, 1961, Ser. No. 66,662

Term of patent 14 years

(Cl. D71—1)

FIG. 1 is a top plan view of a deck hatch for boats showing my new design.

FIG. 2 is a top perspective view thereof.

FIG. 3 is a bottom perspective view thereof in open position.

FIG. 4 is a front perspective view thereof.

FIG. 5 is a front elevation thereof.

FIG. 6 is a side elevation thereof, the opposite side not shown being substantially the same in appearance.

The rear not shown is substantially plain.

The portions shown in broken lines are for illustrative purposes only.

I claim:

The ornamental design of a deck hatch for boats, substantially as shown and described.
